(57) **CLAIM**

The ornamental design for a portable computer as shown and described.

DESCRIPTION

1.1: Front view

1.2: Back view

1.3: Left view

1.4: Right view

1.5: Top view

1.6: Bottom view

1.7: Perspective view

The claimed portions of the portable computer consist of two light strips for emitting light, located along the side surfaces of the top and bottom panels.

The portions of the portable computer, shown in deemphasized half-tone shading between the even-dash broken lines and dash-dot broken lines, form no part of the claimed design. The dash-dot broken lines represent boundaries of the claim and form no part thereof.
